UNITED STATES PATENT OFFICE.

JOHN M. HARTMAN, OF PHILADELPHIA, PENNSYLVANIA.

REGENERATIVE HOT-BLAST STOVE.

SPECIFICATION forming part of Letters Patent No. 353,747, dated December 7, 1886.

Application filed November 17, 1884. Serial No. 148,171. (No model.)

To all whom it may concern:

Be it known that I, JOHN M. HARTMAN, of Philadelphia, in the State of Pennsylvania, have invented certain new and useful Improvements in Regenerative Hot-Blast Stoves, of which the following is a specification reference being had to the accompanying drawings.

Figure 1 is a central vertical section through the stove on a plane at right angles to the division-wall. Fig. 2 is a horizontal sectional view taken upon several planes--viz., as to the quadrant (indicated by X) the section is on the line x x, Fig. 1, as to the quadrant Y on the line y y, Fig. 1, and as to the remainder of the figure (being the quadrants Z Z) on the line z z of Fig. 1. Fig. 3 is a partial vertical section through the side wall and adjacent portion of the checker-work on an enlarged scale. Figs. 4 and 5 are partial horizontal sections on the lines v v and w w, respectively, of Fig. 1.

My invention relates, chiefly, to stoves containing more than one regenerator, and its principal objects are to permit the placing of the combustion-chamber beneath one of the regenerators, to prevent the tearing of the side and division walls and strengthen the roof, to equalize the distribution of the currents while increasing the heating-surface therein, to properly set and support the checker-work, to arrange and work the valves in the most advantageous manner, and to lessen the accumulation and facilitate the removal of dust.

In the drawings, A represents the shell of the stove, inclosing the outer or side wall, B, and stayed at top by the cross-girder a.

C is the combustion-chamber, arranged under one regenerator, D, which is separated from the other regenerator, D', by the division-wall E. The division-wall E is built solid only to the level of the tops of the regenerators, and is pierced above that point by a series of arched openings, e e. The roof of each regenerator is constructed in a separate arch, as shown at b b', the inner end of each arch being supported upon the transverse arches of the division-wall.

The roof of the combustion-chamber C consists of a series of arches whose vertical height is more than half their span, and which may appropriately be termed "Gothic" or "pointed" arches F, arranged parallel to one another and

having intermediate passage-ways. These arches have horizontal tops extending entirely across the chamber, and upon them are supported short transverse brick girders w, upon which the filling of the regenerator D rests.

The tendency of semicircular arches, even when used to support the brace-walls of a combustion-chamber, is to soften and settle in the middle when highly heated, and as, in the arrangement of the regenerator above the combustion-chamber, a much greater weight has to be supported, it is necessary to use the Gothic arch, which is not liable to settle at its center under the effects of heat. To insure, however, the thorough support of the filling in the first regenerator, D, in case the arches F become weakened, it is bonded in with the side and division walls, and as the combustion-chamber is built high and the division-wall does not extend solid above the regenerator, the difference in upward expansion of the first regenerator and wall is very slight. The girders w form the intermediate support between the arches and the regenerator.

The second regenerator, D', being the full height of the stove, I construct it separate from the side and division walls, so that there is no tendency to tear them by unequal expansion. Instead, however, of constructing the bottom of the regenerator D' at one continuous level and supporting it upon a wall or walls parallel to the division-wall E, as is usually the case, I build a wall, G, at right angles to the division-wall, and spring arches h therefrom on each side, said wall G and its side arches being stepped, so that while the bottom of the regenerator D' is in the parts adjacent to the chimney-valve H sufficiently raised to permit access to said valve the inner portions descend as far as possible, leaving only space for the free passage of the gas, &c. The ascending current in the first regenerator is so strong when the foregoing combination and arrangement is used that the gas packs in the top of the stove and distributes itself evenly over the top of the second regenerator, the distribution being also aided by the friction in the smaller passages of the second regenerator. I thus, without increasing the size of the stove, obtain a maximum amount of heating-surface.

The arrangement of the transverse wall G

to support the center of the second regenerator permits the use of much thinner walls and arches than where the whole supporting structure is built parallel to the division-walls, 5 and thus affords more ready access to the bottom of the regenerator for cleaning purposes.

It is usual in lining the shell A to place the bricks forming the side walls radially, and as 10 the checker-work is composed of square or polygonal pieces it does not fit the circular inner surface of the wall, but leaves irregular openings where the checker-work has no lateral support. To avoid this I lay the bricks 15 of one course radially, as shown at f, Figs. 3, 4, and 5, and those of the next succeeding course, g, either at right angles to or parallel with the division-wall E, and so on, allowing the non-radial courses to project inwardly and 20 abut against the sides of the checker-work d, which is thus effectively stayed throughout, the bonding of the wall itself being also improved by these alternate courses.

In the use of hollow brick to form the 25 checker-work it is found impossible to get them all of uniform size, owing to differences in shrinkage, caused by the peculiarities of the clay itself and by irregularities in the burning. It is of great importance, however, that 30 the openings of the regenerator should be in line, as any offsets catch the dust and hinder cleaning. In laying the bricks d of the checker-work I therefore leave a space on all sides of each brick, as indicated in Figs. 4 and 35 5, sufficient to compensate irregularities in size—say one-sixth of an inch—and guide the bricks vertically, by means of the central openings alone, thus insuring a true alignment of the passages. After each course of bricks, 40 fire-clay is spread around the top, so as to flow into the spaces between the bricks and maintain them in position.

The chimney-valve H, I place within the 45 stove itself, by simply bolting the valve-face to the bottom thereof, thus dispensing with the usual outside T-connections, the wall G and outer wall, B, being arched over the valve, as shown in Fig. 1, at i. As the heat at this 50 point is not very great, the shell A of the stove suffices to cover the opening of the arch i.

In order to control the temperature of the blast I introduce a "passover-valve" near the bottom of the division-wall E, thus permitting a portion of the blast to pass directly across 55 without traversing the regenerator. The advantage of this construction is that it prevents explosions from the backing of gas into the air-blast pipe and air-receiver when blast is shut off, a danger which was always incident to the use of a branch pipe extending between the hot-blast and cold-blast pipes and a valve placed at a point between the furnace and stove as formerly used.

The T-connection I at the entrance to the 65 combustion-chamber is controlled by butterfly-valves J. As these valve-disks weigh

some five hundred pounds the scraping upon the bottom of the valve-body is apt to cause so much friction that the valve will not close tight, a difficulty which is increased by the gritty deposit of gas-ashes. I therefore suspend the vertical shaft l of the valve-disk just below its handle k upon the short arm of a lever, m, having an adjustable weight, j, so as to counterbalance the disk.

In the center of the arches b b' of the roof are the doors c c', by which access is had to the top of the regenerators for cleaning purposes. By the alternate passage of gas and blast through the stove the ashes and dust 80 become laminated and adhere so firmly to the sides of the regenerator that they cannot be blown out by the direct current of blast. I have found, however, that by dropping a ball down through the passages of the regenerator 85 while the blast is passing up the current is deflected sidewise against the ashes, &c., with great force, and they are readily detached. I therefore provide a removable spider, q, 90 which rests upon the periphery of the openings c or c', said spider having a depending hinged trough, p, by means of which the balls r (of cast iron or other suitable material) can be discharged into the several passages of the 95 regenerator.

I am aware that it is not new to bind the filling of a regenerator to its walls, and I do not claim this mode of construction; but when the filling is of great height, or when there is unequal expansion in the sides, the walls are liable to be torn; hence my improvement differs from former methods of construction in that while the short regenerator is bonded (thus relieving the strain upon the roof of combustion-chamber to some extent) the long 105 or high regenerator-filling is free to expand, and there is no danger of tearing the walls.

I am also aware, of course, that a Gothic arch is a very old form, and I make no claim to its use, save as one element of the particular combination hereinafter claimed. I believe that I am the first to apply it to a structure whose roof consists of a series of open passages and is required to support a great weight under a very high temperature. In such combination 110 I have discovered that it will not sag or settle in the center as does the arch of semicircular form, and I hence desire to claim this new combination.

Having thus described my invention, I 115 claim—

1. In a single-surface regenerative stove, the combination of the following elements, arranged substantially in the manner specified, viz: a combustion-chamber, a regenerator above the same, a second regenerator equal in height to the combined height of the first regenerator and chamber, and a solid division-wall extending between said regenerators from the bottom of the stove to the level 125 of their tops, the checker-work of the first regenerator being tied or bonded in with the 130

stove-lining and division-wall and the checker-work of the second being built separate from the adjacent walls.

2. In a single-surface regenerator-stove, the combination, with a regenerator, of a subjacent combustion-chamber, a series of Gothic arches with intermediate passage-ways arranged at the top of said combustion-chamber, and a series of transverse girders resting upon said arches and supporting the filling of the said regenerator.

3. In a single-surface regenerative stove of cylindrical form containing two regenerators, the combination of a division-wall between said regenerators, but extending only to the level of their tops, a series of open arches built upon said division-wall, and a double-arched roof the inner ends of whose arches rest upon the arches of the division-wall, substantially as set forth.

4. In a stove of substantially circular horizontal section and having a checker-work of square or polygonal bricks, the combination, with said checker-work, of an inclosing-wall built of alternating courses of bricks, the

brick of one course being laid radially to the circumference of the stove, and those of the next in the direction of chords to said circumference, substantially as set forth.

5. In a regenerative stove containing two regenerators, the combination of a division-wall, E, separating said regenerators, a central wall, G, at right angles to said division-wall, and a series of open arches arranged on each side of and perpendicular to said central wall, said central wall and its side arches forming the support of the second regenerator.

6. The combination, with the regenerator D', of the chimney-valve H, opening downward in the floor of the stove, the central wall, G, having a half-arch, i, over said valve, and the arch in the stove-lining adjacent to said valve.

7. The cold-blast valve arranged at the bottom of the division-wall E, substantially as for the purposes set forth.

JOHN M. HARTMAN.
